DESIGN.

L. N. DOUD.

SLIPPER TREE AND DRESS HANGER.

APPLICATION FILED DEC. 4, 1916.

50,468.

Patented Mar. 20, 1917.

Inventor:
Louis N. Doud

UNITED STATES PATENT OFFICE.

LOUIE NAOMI DOUD, OF NORWALK, OHIO.

DESIGN FOR A SLIPPER-TREE AND DRESS-HANGER.

50,468.

Specification for Design.

Patented Mar. 20, 1917.

Application filed December 4, 1916. Serial No. 135,057. Term of patent $3\frac{1}{2}$ years.

To all whom it may concern:

Be it known that I, LOUIE NAOMI DOUD, a citizen of the United States, residing at Norwalk, in the county of Huron and State of Ohio, have invented a new, original, and ornamental Design for a Slipper-Tree and Dress-Hanger, of which the following is a specification, reference being had to the accompanying drawing, forming part thereof.

The figure is a front elevation of a slipper-tree and dress hanger illustrating my new design.

I claim:

The ornamental design for a slipper-tree and dress-hanger, as shown.

LOUIE NAOMI DOUD.

Witnesses:

CHARLES SULER,
J. M. BECHTOL.
